WILLIAM SMITH, OF CINCINNATI, OHIO.

Letters Patent No. 82,360, dated September 22, 1868.

IMPROVED FOLDING TABLE.

The Schedule referred to in these Letters Patent and making part of the same.

TO WHOM IT MAY CONCERN:

Be it known that I, WILLIAM SMITH, of Cincinnati, Hamilton county, Ohio, have invented a new and useful Improvement in Tables; and I hereby declare the following to be a full, clear, and exact description thereof, reference being had to the accompanying drawing, making part of this specification.

This invention relates to that class of tables whose legs are capable of being folded up so as to economize space in transportation and in crowded apartments; and my invention consists more particularly in certain devices for facilitating the unfolding and folding of the legs, and also for retaining them securely in their opened position.

The accompanying drawing is a perspective view of a table embodying my improvement, the table being in an inverted position, and having one pair of legs secured in opened position, while the other pair is represented as partially folded up.

A represents the table-top, to whose under side are hinged, at a , two frames, consisting of upper rails, B C, and lower ones, D E, while the legs F of the table are secured to the ends of these rails.

G are braces, whose lower ends are hinged to the bottom rails, at d d' and e e' , while the upper ends of said braces are hinged at g to the slides H, which slides are adapted to traverse grooves I, the latter being formed by the cleats i, that are attached to the under side of the table-top. As these cleats are under-cut, and the slides are of corresponding shape, there is no danger of said slides becoming detached from the grooves I.

The grooves I have secured within them stops J, against which the slides H abut, when the legs F are in their opened position. K are ordinary spring-bolts, which protrude and bear against the inner ends of the slides H, and thereby prevent the accidental displacement of the legs F when they are unfolded; as shown in the drawing.

When it is desired to use the table, the legs can be unfolded in a moment, by simply grasping the bottom rails D E, and elevating the same, which causes the slides H to traverse the grooves I, and as soon as said slides come in contact with the stops J, the spring-bolts K immediately fly out in the rear of the slides, and thus secure the legs in their opened position, and in such a manner as to prevent their being accidentally displaced in case they should be struck by a person in passing the table.

The legs can be folded up by retracting the spring-bolts, and pressing down upon the rails D E, so as to cause said legs to assume the position shown at the nearest end of the table in the drawings, and when in this condition, a number of tables can be stacked one upon another, thereby economizing room, and rendering them capable of being transported with the greatest facility, and without any danger of breaking off the legs or marring the table-tops.

If preferred, suitable notches can be made in the side of the braces G, so as to receive the spring-bolts K when the legs are completely folded up.

For paper-hangers, marketmen, and other who desire a very light and portable table, only one of the braces G need be used for each pair of legs, in which case said braces should be attached to the mid-length of the bottom rails D E.

I claim herein as new, and of my invention—

The combination, substantially as described, of the table A, hinged frames a B C D E, legs F, hinged braces G g d d' e e' , slides H, under-cut grooves I i, stops J, and spring-bolts or catches K, or their mechanical equivalents, for the object explained.

In testimony of which invention, I hereunto set my hand.

W. SMITH.
